BAG

Adolph Potdevin, Garden City, N. Y., assignor to
 Potdevin Machine Company, Brooklyn, N. Y., a
 corporation of New York

Application November 17, 1936, Serial No. 111,189

1 Claim. (Cl. 229—62.5)

This invention relates to improvements in valve bags and to the method of making the same.

One of the objects of the present invention is the provision of a valve bag in which one end 5 of the bag tubing is formed in a novel manner so that when the tubing is folded inwardly at one edge of the bag a new and improved form of valve is provided.

A further object of this invention is the provision of a valve bag, the valve of which is so shaped that perfect functioning of the valve is assured, the valve or valve flap being so formed that the valve will adjust itself more uniformly to the contour of the inside of the filled bag than is possible with prior structures.

My invention has for a further object the provision of a construction in which a saving in material is effected, this being of material importance, particularly in the case of multi-wall bags.

Other objects of my present invention will be manifest from the following description and the accompanying drawing, in which:

Fig. 1 is a plan view illustrating the manner in which the bag tubing is divided into bag lengths;

Fig. 2 is a plan view showing a preliminary step in forming the valve and closing the valve end of the bag;

Fig. 3 is a view showing the valve end of the bag in closed position;

Fig. 4 is a view on line 5—5 of Fig. 3; and

Fig. 5 is a view on line 6—6 of Fig. 3.

Referring to the drawing in detail: 2 designates the bag tubing which is to be severed into bag lengths 4 in accordance with my invention. The tubing is severed transversely along lines 6. These lines of severance are a distinct departure from the straight line of severance of prior practice. The line of severance 6 in the upper wall of the tubing begins at one edge of the tubing with a short straight transverse cut 10; the cut then curving inwardly as shown at 12 and from thence extending in a straight transverse line 14 to 16 adjacent the other edge of the tube, where it curves outwardly as indicated at 18.

The lower wall of the tubing has a short transverse cut corresponding to cut 10 in the upper wall. This cut is then curved outwardly as shown at 20, and then continues in a straight transverse cut 22 parallel to the straight cut 14 in the upper wall. This straight cut 22 merges into a curve adjacent the opposite edge of the tubing which corresponds to the curved cut 18 in the upper wall.

It is the curved cut 18 in the upper wall of the tubing and the corresponding curved cut in the

lower wall which provides the novel flap of the invention.

It will be appreciated that the parallel cuts 14 and 22 are offset with respect to each other.

It will be seen from Fig. 1 that a slit 28 is 5 provided in the valve end of the bag length, at the side opposite the valve flap, to facilitate bottoming of the bag. There is no slit, however, at the opposite side or valve side of the bag length so that all of the material at this corner of the 10 bag length is available for valve flap purposes.

When the bag lengths have been severed from the tubing the ends are opened up and the lower wall 30 and upper wall 32 folded back upon themselves as illustrated in Fig. 2, the corner 34 folded 15 inwardly and the valve corner 36. Paste or adhesive is then applied as shown, and the upper wall 32 folded down along the line 38, and the lower wall 30 folded over upon it along the line 40. The finished bottom is shown in Fig. 3. It 20 will be seen from this drawing that by omitting the slits at the valve side of the bag length this entire corner is available for valve flap purposes. It will be seen also that this gives a different appearance to this corner of the bag bottom, so 25 that the valve corner is readily distinguishable.

It will be appreciated that by curving the inner end of the valve flap as shown at 18 in Fig. 2, the valve will readily conform to the interior of the bag bottom.

It will be appreciated, furthermore, that with each bag length there is a saving in material as compared with bag lengths made by so cutting through the bag tubing that both walls of the bag length are of the same length equal to the space between the end 14 of the upper wall and the end 22 of the lower wall of the bag length. This amounts to about $\frac{1}{8}$ " to $\frac{3}{4}$ " in a 3" bottom.

It is to be understood that various changes and modifications may be made in the method of producing my improved bag as well as in the bag itself without departing from the spirit and scope of my invention.

What I claim is:—

As an article of manufacture, a bag length, 45 one wall of which at one end of the bag length projects throughout the major portion of the width of the bag length beyond the other wall, both walls adjacent one edge of the bag length at the said end of the bag length being curved outwardly, this curved portion being turned inwardly 50 transversely of the bag length between the walls of the bag length to provide a valve flap, the open or filling end of which is convex.
